 PLLC; David W. Nagle, Jr.; James R. Hayne(57) **CLAIM**

The ornamental design for a beverage dispenser, as shown and described.

DESCRIPTION

FIG. 1 is a perspective view of a beverage dispenser incorporating the design of the present invention;

FIG. 2 is a front view of the beverage dispenser of FIG. 1; FIG. 3 is a rear view of the beverage dispenser of FIG. 1; FIG. 4 is a left side view of the beverage dispenser of FIG. 1;

FIG. 5 is a right side view of the beverage dispenser of FIG. 1;

FIG. 6 is a top view of the beverage dispenser of FIG. 1; and, FIG. 7 is a bottom view of the beverage dispenser of FIG. 1.

The broken lines in FIG. 7 depict portions of the beverage dispenser that form no part of the claimed design.
